UNITED STATES PATENT OFFICE

FRANCIS M. LAMBERT, OF NARBERTH, PENNSYLVANIA, ASSIGNOR TO HEINTZ MANUFACTURING COMPANY, A CORPORATION OF PENNSYLVANIA

DESIGN FOR A RADIATOR CABINET

Application filed May 21, 1929. Serial No. 31,323. Term of patent 7 years.

To all whom it may concern:

Be it known that I, FRANCIS M. LAMBERT, a citizen of the United States, residing at Narberth, in the county of Montgomery and State of Pennsylvania, have invented a new, original, and ornamental Design for Radiator Cabinets, of which the following is a specification, reference being had to the ac-

companying drawing, forming a part thereof.

In the drawing, the figure is a perspective view of a radiator cabinet, showing my new design.

I claim:

The ornamental design for a radiator cabinet, as shown.

FRANCIS M. LAMBERT.
